UNITED STATES PATENT OFFICE.

JOSEPH BINKS, OF RIVER FOREST, ILLINOIS.

DESIGN FOR A VALVE-DISK.

SPECIFICATION forming part of Design No. 28,570, dated May 10, 1898.

Application filed April 18, 1898. Serial No. 673,010. Term of patent 7 years.

To all whom it may concern:

Be it known that I, JOSEPH BINKS, a citizen of the United States, residing at River Forest, county of Cook, and State of Illinois, have invented and produced a new and original Design for Valve-Disks, of which the following is a specification, reference being had to the accompanying drawings, forming a part thereof.

Figure 1 is a plan view of the disk, and Fig. 2 is a sectional view on the line 2 2 of Fig. 1.

The leading features of my design consist of a flat disk A, having a central circular aperture B, an annular flange C of greater diameter than the aperture B, rising from one side of the disk A and having recesses c c,

which extend through the entire width of the flange, and an annular flange D, the internal diameter of which is the same as the diameter of the aperture B, rising from the opposite face of the disk A.

Having described my invention, what I claim as new, and desire to secure by Letters Patent, is—

The design for a valve-disk, as herein shown and described.

JOSEPH BINKS.
